FUEL OIL COMPOSITIONS CONTAINING
ANTIMICROBIAL AGENTSClaude R. Summers, Jr., Havertown, Pa., assignor to
Gulf Oil Corporation, Pittsburgh, Pa., a corporation of
Pennsylvania

No Drawing. Filed Sept. 29, 1955, Ser. No. 537,585

9 Claims. (Cl. 44—56)

This invention relates to fuel oil compositions containing anti-microbial agents, and more particularly to fuel oil compositions that tend to deposit gels derived from gel-forming microorganisms, and that contain a small amount of an anti-microbial agent effective to destroy said gel-forming microorganisms. The invention also includes methods of treating fuel oils of the type described in order to reduce gel deposition.

Numerous East Coast marketers of distillate fuel oils have recently received increasing numbers of complaints because of malfunctioning of distillate fuel oil burners due to accumulations of gelatinous deposits in fuel lines, strainers, burner nozzles, filters, needle valves, level controls, and the like. In numerous instances physical removal of the gelatinous deposits has failed to provide more than temporary relief, with the result that further service calls have been necessary to remove additional gel deposits, often within as short a time as 7 days or less. Thus, many burner installations show a history of repeated service calls due to gel deposits within the course of a single heating season.

As an indication of the seriousness of this problem it may be mentioned that a recent survey of distillate fuel oil burner installations in a region where complaints due to gel deposition have been received in the past indicated that malfunctioning of the oil burners due to gel deposition might be expected at some time in the reasonably foreseeable future in two-thirds of the installations examined.

Because of the novel appearance of these fuel oil gel deposits and because of their persistence in the face of ordinary methods used to combat fuel oil deposits such as sludge, and because of other factors, it was recognized that the problem of fuel oil gels was new and distinct from previous problems of distillate fuel oil deposits.

Systematic attempts to trace the cause of fuel oil gel deposits to an entirely chemical source, such as for example, chemical impurities, degradation or decomposition of one or more of the petroleum components of the fuel oils, or to chemical additives included in the fuel oil to improve one or more of its properties, have not been successful.

It has now been found that these fuel oil gels are of microbial derivation, and that they are due to the presence of gel-forming microorganisms in the fuel oil as such and/or in water entrained by or contacted by the fuel oil. It has further been found that the problem of gel deposition in distillate fuel oils that normally tend to deposit gels can be greatly alleviated by treating the oils with a small amount of an anti-microbial agent that is effective to kill said fuel oil gel-forming microorganisms. The present invention therefore includes fuel oil compositions which comprise a major proportion of a distillate fuel oil that normally tends to deposit gels due to the presence of gel-forming microorganisms, and a microbial proportion of an anti-microbial agent that is effective to kill the fuel oil gel-forming microorganisms. The invention also includes treatment of distillate fuel

oils of the kind described with anti-microbial agents to reduce gel deposition.

The fuel oil gels with which this invention is concerned have been found to occur mostly in the form of beads and films. Occasionally, however, the gel deposits are in fibrous form. When in relatively pure form the fuel oil gels have been found to be clear and generally yellowish in color, but these characteristics are sometimes masked by contamination of the gel with black fuel oil sludge or other minute particles of debris normally present in the fuel oil.

Chemical analysis of a large number of samples of these fuel oil gels shows that they all contain significant proportions of water, sulfur and copper. Where the fuel oils contain chemical addition agents, such as for example sludge inhibitors, appreciable proportions of chemical components traceable to these additives, or the additives themselves, may be found in the gels. By way of illustrating the chemical composition of these gels there are presented below analytical data on two samples of fuel oil gels removed from different burner installations. In both instances the gel as such was separated from concomitant fuel oil and sediment by heating the crude sample originally removed from the burner installation to 120° F. and then filtering through a No. 12 Whatman filter paper.

55	The gel sample from Installation B also indicated the presence of the commercial fuel oil sludge inhibitor employed in the fuel oil. The gel sample from Installation A was not tested for the presence of sludge inhibitor.		
60	With respect to the significant components of the gels, the sulfur content is probably traceable directly or indirectly to the sulfur content of the distillate fuel oil. Whether sulfur accelerates or is essential to gel deposition has not been definitely determined. However, it may be significant that the problem of gel deposition has followed the manufacture of distillate fuel oils from crude oils of relatively high sulfur content. The water content of the gels is probably traceable to moisture entrained in the fuel oil, which can be present as a result of steam stripping of the fuel oil during distillation of the latter, as a result of contact with residual water in storage tanks or the tanks of marine transport vessels, as a result of condensed moisture from the atmosphere, or as a result of other causes. Experimental evidence indicates that water tends to promote gel formation. The copper present in the gels appears to be traceable to copper fuel feed lines in burner installations or to the		
65			
70			

copper or brass parts of floats, valves, screens or other copper-containing parts of the installations. Experimental evidence also indicates that copper tends to promote fuel oil gel deposits.

A systematic investigation of a large number of samples of fuel oil gels has revealed in every instance the presence of an apparently pure strain of living microorganism, and all available evidence points to these microorganisms as the cause of the fuel oil gels. It is somewhat surprising to find that any microorganism can survive and multiply in the fuel oil, which may account, at least in part, for the apparent purity of the strain. Moreover, it has been found that a gel can be produced in incubated samples of previously sterilized fuel oil by inoculation of the fuel oil with a small amount of the gel-forming microorganisms taken from oil burner installations containing fuel oil gel deposits. It has also been found that the addition of water to the fuel oil appears to promote the development of the gels. Furthermore, when a piece of copper wire is placed in the fuel oil, gel formation appears to be promoted. Gel formation appeared to be especially favored in fuel oil samples that had been inoculated with gel-forming microorganisms and that were maintained in contact with both metallic copper and water containing organic matter capable of supporting microbial life. Whether the fuel oil gels are produced as such by the microorganisms, or whether the microorganisms merely transform fuel oil components and/or materials contained therein or contacted thereby to gel-forming materials, is not clear. The latter possibility would seem to find some support in the fact that gels resembling those found in the field have been prepared in the laboratory from a mixture of dodecyl and xylyl mercaptans and oil-soluble copper naphthenate.

Under a magnification of 430 times, the fuel oil gel-forming microorganisms appear as a mass of multicellular filaments. The filaments show branching, and there is evidence of reproduction by budding. These characteristics are typical of yeast-like microorganisms.

The exact identity of these gel-forming microorganisms is difficult to ascertain, and therefore the invention is not limited to any specific scientific class of microorganism. The fuel oil gel-forming microorganisms may be a species of sulfur-utilizing filamentous bacteria of the Beggiaaceae family, e.g., Beggiaota, as might be suggested by the consistent presence of sulfur in the gels. However, available evidence is conflicting as to whether the fuel oil gel-forming microorganisms thrive in contact with sulfur. The possibility that the gel-forming microorganisms are of the Beggiaaceae family would appear to be more or less negated by the fact that these gel-forming microorganisms appear under magnification as multicellular branched Hyphae, and by the fact that they appear to reproduce by budding, which facts are characteristic of fungi such as Hyphomycetales, such as for example species of *Pullularia* or *Monilia*, i.e., *Candida*. Photomicrographs of the gel-forming microorganisms show a particularly marked similarity to those of a microorganism previously identified as a species of *Monilia*. The fact that some strains of the genus *Monilia* are known to form mucous or gelatinous masses may be significant insofar as the present problem is concerned.

In what manner the distillate fuel oils have become infected has not been established because of the many possible sources of contamination, such as for example contact with residual water in stationary storage tanks or storage tanks of marine transports, decaying vegetation, or merely air. In this connection it may be pertinent to note that species of *Monilia* have been found as contaminants in air.

As indicated above it has been found that the problem of gel deposition in distillate fuel oils can be alleviated by treatment thereof with anti-microbial agents. Anti-microbial agents that are suitable for the purposes of this invention are those that are capable of destroying or

killing the fuel oil gel-forming microorganisms. An example of an excellent anti-microbial agent of the kind included by this invention is n-propyl Formcel which is a commercial bactericide consisting of a 40 percent solution of formaldehyde in n-propyl alcohol. Examples of other anti-microbial agents that are effective to destroy fuel oil gel-forming microorganisms are n-propyl alcohol and orthophenylphenol (Dowicide 1). Although each of the above disclosed anti-microbial agents is soluble in distillate fuel oil in microbial proportions, the invention is not restricted to the use of oil-soluble anti-microbial agents, and water-soluble, oil-insoluble anti-microbial agents can be used. An example of such an agent is a mixture of alkyltolylmethyl trimethyl ammonium chlorides containing alkyl groups ranging from C_9H_{19} to $C_{15}H_{31}$. This agent is a commercial anti-microbial agent marketed as a 50 percent aqueous solution under the name "Hyamine 2389" by Rohm & Haas. An example of another water-soluble anti-microbial agent effective to destroy fuel oil gel-forming microorganisms is a mixture of alkyldimethylbenzylammonium chlorides wherein the alkyl groups are from C_8H_{17} to $C_{18}H_{37}$. This material is marketed under the name "Roccal" by the Sterwin Chemical Company. The invention lends itself to the use of water-soluble, oil-insoluble anti-microbial agents in different ways. Thus, the water-soluble anti-microbial agents may be incorporated in the infected fuel oils by the use of dispersing agents, mutual solvents or blending agents that are compatible with the fuel oil and the anti-microbial agent and that do not materially impair the anti-microbial properties of the latter, in an amount sufficient to provide a homogeneous composition. Examples of anti-microbial agent-containing concentrates containing blending agents suitable for the purposes of this invention are concentrated solutions containing, for example, 10, 20 or 35 percent Roccal in acetone, alcohol or glycerine.

Alternatively, in view of the fact that the fuel oil gels with which this invention is concerned consistently have been found to contain water, and in view of the fact that the gel-forming microorganisms appear to thrive at a water-fuel oil interface, the invention also lends itself to treatment of fuel oils that tend to deposit gels with water solutions of oil-insoluble anti-microbial agents. Thus, for example, in the practice of the invention by this method, Roccal or Hyamine 2389 as such or diluted with water can be added to the water layer in a fuel oil tank. Normally, an aqueous phase of about 0 to 5 gallons will be found at the bottom of a 275 gallon fuel oil tank. The amount of Roccal, Hyamine 2389 or other water-soluble anti-microbial agent added to the tank can be adjusted to provide the ultimate concentration desired in the aqueous phase, e.g., 0.01 volume percent or more.

As indicated, the above-specified anti-microbial agents are illustrative only and the present invention is not restricted to their use. Other anti-microbial agents capable of killing the fuel oil gel-forming microorganisms can be used. Although the action of the anti-microbial agents upon the gel-forming microorganisms with which this invention is concerned is apparently quite selective, other suitable anti-microbial agents can be determined by trial and error, or preferably, by laboratory scale tests. For example cultures of the gel-forming microorganisms can be prepared by inoculation of agar plates, and after growth colonies become distinguishable, several drops of the anti-microbial disinfectant being tested can be applied at points on the agar plate where the colonies appear. The culture plates can then be incubated at a temperature favorable to the growth of the microorganisms, e.g., 37° C., and examined for microbial growth after 24 and 72 hours. If no growth is evident during these examinations it can be assumed that the organisms have been destroyed. Fuel oil solutions containing respectively 0.1 volume percent n-propyl Formcel, n-propyl alcohol and o-phenylphenol, and water solutions containing, respec-

tively 0.1 volume percent of Roccal and Hyamine 2389 have proved effective under the conditions of this test.

The addition of small amounts of anti-microbial agents of the type disclosed herein to fuel oils that tend to deposit gels of microbial derivation has been found to produce excellent results. The anti-microbial agents of this invention should be used in concentrations effective to destroy the gel-forming microorganisms, i.e., in microbicidal proportions. The optimum concentration of the anti-microbial agents of this invention may, of course, vary with the nature of the individual agents themselves and possibly in some instances according to the degree of infection of the fuel oil by gel-forming microorganisms. Generally speaking, highly effective results will be obtained by addition to the fuel oil, or to aqueous phase material in contact therewith, of anti-microbial agents of the kind disclosed herein in amounts of between about 0.05 and about 0.5 volume percent. For example, excellent results have been obtained by the use of an 0.1 volume percent concentration. In individual instances, for example, those involving a low degree of infection by the gel-forming microorganisms and/or highly effective anti-microbial agents, concentrations of anti-microbial agents as low as 0.01 volume percent or less can be used. On the other hand, in instances involving a high degree of fuel oil infection and/or a relatively less active anti-microbial agent, concentrations of anti-microbial agent in excess of 0.5 volume percent, for example up to 1.0 volume percent, or possibly more, may be necessary. However, in no instance should the concentration of the additive be so great as to materially impair the ignition or combustibility characteristics of the fuel oil.

The anti-microbial agents disclosed herein can be used to treat the distillate fuel oils that tend to deposit gels of microbial derivation in any suitable manner. For example, oil-soluble anti-microbial agents of the class disclosed herein or in the form of concentrated solutions in compatible solvents, can be added as such, directly to the fuel oils at the refinery. However, because of the fact that gel deposition due to gel-forming micro-

due to the presence of gel-forming microorganisms. A specific example of a fuel oil, the treatment of which is included by this invention, is No. 2 fuel oil, a type of distillate fuel oil used for domestic heating and light industrial heating purposes. A No. 2 fuel oil is defined in the ASTM Standards on Petroleum Products and Lubricants, under the specification designated D-396-48T. Specific examples of other distillate fuel oils included by the invention are diesel fuels and No. 1 fuel oil. It is noted that the problem of gel formation due to micro-organisms appears to be restricted to distillate fuel oils. The reason for this apparent selectivity is not certain, but it may be due to the characteristically high sulfur content of these fuel oils, or it may be due to the nature of the conditions under which these oils are used. Thus, these oils are normally used in installations involving relatively long term storage in contact with water and copper.

The terms "microbial," "anti-microbial," "microbicidal" and the like are used herein in their broader sense and as such have reference to microbes or microorganisms broadly, whether or not they are pathogenic.

Fuel oil compositions within the scope of this invention are illustrated by the following specific examples.

25

EXAMPLE I

A fuel oil composition according to this invention was prepared by incorporation of 0.1 volume percent of n-propyl Formcel in a No. 2 fuel oil of the kind tending to deposit gels due to the presence of gel-forming microorganisms and which contained a commercial sludge inhibitor. The n-propyl Formcel used in the composition had the following properties:

Gravity: ° API	13.5
Viscosity SUV: sec., 77° F.	137.9
Flash, OC: ° F.	132
Pour: ° F.	Below -70

The relatively small change in the properties of the fuel oil brought about by the use therein of 0.1 volume percent n-propyl Formcel is illustrated by the following inspections:

	Uninhibited Fuel Oil Stock	Fuel Oil Stock+ Sludge Inhibitor	Example I Fuel Oil Composi- tion
Make-up, Percent by Volume:			
No. 2 Fuel Oil Stock	100	100	100
Inhibitor Added, Percent by Volume—

¹ Barium long-chain alkyl benzene sulfonate, 50% oil solution.

ganisms has not proved to be a problem in all burner installations, it may be preferable for the anti-microbial agents to be incorporated in the fuel oil in the tanks of fuel oil retailers, or in the tanks of individual burner installations. When blending agents are employed therewith, oil-insoluble anti-microbial agents can be incorporated into the fuel oil similarly as oil-soluble agents. Normally, some agitation is desirable during admixture of the anti-microbial agents with the fuel oil, but this is not essential. The manner of treatment of fuel oil in the instance of oil-insoluble anti-microbial agents in the absence of blending agents has been indicated previously.

Fuel oils that can be treated according to this invention are those distillate fuel oils that tend to deposit gels

65 Another distillate fuel oil composition according to this invention was prepared by incorporation of 0.1 volume percent o-phenylphenol in a No. 2 fuel oil of the kind tending to deposit gels and having the following inspections:

Gravity: ° API	37
Flash, PM: ° F.	150
Color, ASTM Union	1.0
Distillation, ° F.: Over	367
End	650

7
EXAMPLE III

Another distillate fuel oil composition according to this invention was prepared by incorporation of 0.1 volume percent n-propyl alcohol into the base fuel oil of Example II.

The foregoing examples are illustrative only and other fuel compositions normally tending to deposit gels due to the presence of gel-forming microorganisms can be treated and prepared according to this invention by incorporation therein of other anti-microbial agents that are effective for the purposes of this invention, in the same or equivalent proportions. For example, to either of the base fuel oil compositions of Examples I and II there can be added 0.1 volume percent Roccal or Hyamine 2389 in a blending agent of the kind described previously.

By way of further illustrating the effectiveness of this invention in combating fuel oil gels, it can be noted that

forming microorganisms found present, nor was there any evidence of new gel formation in these installations. In some cases where some or all of the gel was purposefully left intact, the gel was found to be reduced in quantity or eliminated. One of the untreated installations which at the first visit had contained no gel but which contained gel-forming microorganisms was found to have developed the gel during 45 days elapsed between visits. A second gel-containing, untreated installation failed to develop gel in 14 days, but still contained gel-forming microorganisms after this period. A third non-gel-containing installation which had been treated with n-propyl Formcel was found to have no gel deposits or gel-forming microorganisms after 15 days. In the table following there are presented the test results obtained in several individual instances considered more or less representative of the entire test.

a full scale test was carried out involving a number of actual burner installations using No. 2 fuel oil and known or suspected to have a problem due to gel deposits. Of the total installations involved in the test complete results were obtained on 26 burner installations divided among several relatively widely separated geographical areas. At the outset of the investigation, samples of fuel oil were taken from 25 of these 26 installations and upon microscopic examination, each sample proved to contain gel-forming microorganisms. Gel deposits, occurring in the form of films, beads, or fibers, in the order of prevalence named, were found in 23 of the 26 installations and the volume of gel found was rated as trace, light, medium, or heavy. All of the installations in which gel was found were treated with n-propyl Formcel in the proportion of about 0.1 volume percent, in some instances with and in others without agitation. In most instances the gel was physically removed from the place where found, but in several installations some or all of the gel was left intact. After periods ranging from about 12 to about 45 days, the same 26 installations were again checked for gel, and fuel oil samples were again taken for microscopic examination. In none of the 23 installations where the n-propyl Formcel was added were gel-

In the foregoing table under the column headed "Method of Treatment," the letter entries have the following meanings:

- 55 A, agent added through fill line without agitation.
 B, agent added through fill line; agitation obtained by fuel delivery.
 C, agent added through fill line; agitated by hand.
 D, agent blown through feed line into tank and agitated.

60 Entries opposite No. 1 in the foregoing table are illustrative of treatment of an installation involving heavy gel deposits in film form by addition of the anti-microbial agent through the fill line without agitation. Entries 65 opposite No. 2 in the foregoing table indicate treatment of an installation where no gel was found at the first visit and no anti-microbial agent was employed. Entries opposite No. 3 in the foregoing table illustrate treatment of an installation where the gel found in the system was left intact. Entries opposite No. 4 in the foregoing table illustrate treatment of an installation containing bead-like gel deposits. Entries opposite No. 5 in the foregoing table are illustrative of treatment of an installation containing fibrous gel deposits, using a different method of introducing the anti-microbial agent.

Entries opposite No. 6 and No. 7 in the foregoing table are illustrative of treatment of installation using still other methods of introducing the anti-microbial agent.

If desired, the fuel oil compositions of this invention may contain, in addition to the compounds previously discussed, oxidation inhibitors, flash point control agents, corrosion inhibitors, antifoam agents, ignition quality improvers, combustion improvers, other sludge inhibitors, and other additives adapted to improve the oils in one or more respects.

Obviously many modifications of the invention, as hereinbefore set forth, may be made without departing from the spirit and scope thereof, and therefore only such limitations should be imposed as are indicated in the appended claims.

I claim:

1. A fuel oil composition comprising a major proportion of a distillate fuel oil in contact with an aqueous phase and tending to deposit gels that contain water, sulfur and copper, due to the presence in at least one of said oil and said aqueous phase of microorganisms that promote deposition of such gels, and a microbicidal amount of an anti-microbial agent that is effective to destroy said gel-promoting microorganisms.

2. The fuel oil composition of claim 1 wherein said microbicidal amount is about 0.01 to about 1.0 volume percent of the composition.

3. The fuel oil composition of claim 1 wherein said microbicidal amount is about 0.05 to about 0.5 volume percent of the composition.

4. A fuel oil composition comprising a major proportion of a distillate fuel oil in contact with an aqueous phase and tending to deposit gels that contain water, sulfur and copper, due to the presence in at least one of said oil and said aqueous phase of microorganisms that promote deposition of such gels, and a microbicidal amount of an anti-microbial agent effective to destroy said gel-promoting microorganisms, said anti-microbial agent being selected from the group consisting of n-propyl alcohol, a 40 percent solution of formaldehyde in n-propyl alcohol, o-phenylphenol, mixed alkyltolylmethyl trimethyl ammonium chlorides whose alkyl groups contain 9 to 15 carbon atoms, and mixed alkylidimethylbenzylammonium chlorides whose alkyl groups contain 8 to 18 carbon atoms.

5. A fuel oil composition comprising a major proportion of a distillate fuel oil in contact with an aqueous phase and that tends to deposit gels that contain water, sulfur and copper, due to the presence in at least one of said oil and said aqueous phase of microorganisms that promote deposition of such gels, and a microbicidal amount of a 40 percent solution of formaldehyde in n-propyl alcohol.

6. A fuel oil composition comprising a major proportion of a distillate fuel oil in contact with an aqueous phase and that tends to deposit gels that contain water, sulfur and copper, due to the presence in at least one of said oil and said aqueous phase of microorganisms that promote deposition of such gels, and a microbicidal amount of n-propyl alcohol.

7. A fuel oil composition comprising a major proportion of a distillate fuel oil in contact with an aqueous phase and that tends to deposit gels that contain water, sulfur and copper, due to the presence in at least one of said oil and said aqueous phase of microorganisms that promote deposition of such gels, and a microbicidal amount of o-phenylphenol.

15 8. A fuel oil composition comprising a major proportion of a distillate fuel oil in contact with an aqueous phase and that tends to deposit gels that contain water, sulfur and copper, due to the presence in at least one of said oil and said aqueous phase of microorganisms that promote deposition of such gels, and a microbicidal amount of mixed alkyltolylmethyl trimethyl ammonium chlorides whose alkyl groups contain 9 to 15 carbon atoms.

20 9. A fuel oil composition comprising a major proportion of a distillate fuel oil in contact with an aqueous phase and that tends to deposit gels that contain water, sulfur and copper, due to the presence in at least one of said oil and said aqueous phase of microorganisms that promote deposition of such gels, and a microbicidal amount of mixed alkylidimethylbenzyl-ammonium chlorides whose alkyl groups contain 8 to 18 carbon atoms.
